Leroy O. Schneeberger, St. Louis, Mo.

Application May 12, 1948, Serial No. 146,332

Term of patent 14 years

(Cl. D80—9)

To all whom it may concern:

Be it known that I, Leroy O. Schneeberger, a citizen of the United States and a resident of the city of St. Louis and State of Missouri, have invented a new, original, and ornamental Design for Bottle Display Stand, of which the following is a specification, reference being had to the accompanying drawing, forming part thereof.

Fig. 1 is a front elevational view of a bottle display stand, showing my new design.

Fig. 2 is a rear elevational view.

Fig. 3 is a side elevational view.

Fig. 4 is a top plan view; and

Fig. 5 is a perspective view.

I claim:

The ornamental design for a bottle display stand, substantially as shown.

LEROY O. SCHNEEBERGER.
